UNITED STATES PATENT OFFICE.

JAMES SHEWAN, OF NIAGARA FALLS, NEW YORK.

DINNER-PAIL.

1,100,202.

Specification of Letters Patent. Patented June 16, 1914.

Application filed July 2, 1912. Serial No. 707,278.

To all whom it may concern:

Be it known that I, JAMES SHEWAN, a subject of the King of Great Britain, residing at Niagara Falls, in the county of Niagara and State of New York, have invented new and useful Improvements in Dinner-Pails, of which the following is a specification.

The present invention relates to dinner buckets.

10 In carrying out my invention it is my purpose to provide a dinner bucket comprising a plurality of super-imposed compartments, each adapted to receive separate articles of food, and each removable one from 15 the other, means being provided for sustaining the said sections one above the other, the sections being telescoped one with the other, and the said retaining means being also adapted to retain the sections or compartments 20 when telescoped within each other, and which thus provides a comparatively small package which may be easily carried by the user.

A still further object of the invention is 25 the provision of a heating apparatus arranged within the lower compartment, and whereby the food within any of the said compartments may be heated when desired.

With the above recited objects in view, the 30 invention resides in the novel construction, combination and operative arrangement of parts set forth in the following description and falling within the scope of the appended claim.

35 In the drawing, Figure 1 is an end elevation of a dinner bucket constructed in accordance with the present invention, the sections comprising the bucket being raised one above the other as when food is arranged within the compartments. Fig. 2 is a 40 similar view, but illustrating the sections telescoped within each other when the food has been removed from the compartments. Fig. 3 is a vertical longitudinal sectional view upon the line 3—3 of Fig. 1.

The dinner bucket A is made up of a plurality of sections, the lower section 1 providing a heating chamber. This section has its walls formed with openings 2 for the 45 circulation of air, and whereby a free combustion may be obtained when the heater 3, which is arranged therein, is lighted. The section 1 is provided upon its opposite ends with spring members 4, the latter comprising 50 flattened elements which have their lower ends secured to the said section 1, as

at 5, while the portions of the springs projecting above the said compartment are provided with spaced openings which are designated by the numerals 6 and 7 respectively. 60 The section 1 is furthermore provided with a horizontally disposed bead 1^a arranged around its upper edge, the said bead acting as a means for keeping the projecting portion of the flat springs 4 in an outwardly 65 inclined position so as to permit the free end of the said spring portion to be easily grasped when it is desired to telescopically place the upper section within the lower one. Arranged within the section 1 is a food compartment 8, the same having its sides provided with clips 9 which are adapted to receive the free ends of the bail or handle 10 for the bucket. The sides of the compartment 8 are further provided with studs, the 70 said studs adapted to engage within the openings 6 of the springs 4 when the compartment is in the position illustrated in Figs. 1 and 2 of the drawings, and the said studs being adapted to engage within the 75 opening 7 when the compartment 8 is telescoped within the section 1, as illustrated in Fig. 2 of the drawing. The closed bottom of the compartment 8 is formed with a depressed portion 12, the latter being of a sufficient 80 size to receive the heater 3 when the compartment 8 is in its lowered position within the section 1. The upper and open end of the compartment 8 is provided with a continuous bead, which is designated by 85 the numeral 13, and the said bead is adapted to serve as a stop and a support for a food compartment 14, the said compartment being approximately centrally beaded or flanged as at 15 and the said flange is adapted to contact with the bead 13. The compartment 14 is provided with a closed bottom and open top and normally closing the 90 said open top is the uppermost compartment 16. This compartment 16 is provided with a flange 17 which contacts with the upper beaded edge of the compartment 14, and the compartment 16 is normally closed through the medium of a suitable cover 18. The lower section 1 is preferably provided 100 with flanges 19 which form a pocket for the heater, and the said heater is also preferably provided with a closure 20.

Having thus described the invention, what I claim is:

110 A dinner pail comprising a lower section having a flange extending from its upper

edge, a second section slightly smaller than said lower section so as to be capable of telescoping into the same, outstanding studs on opposite walls of said second section, and
5 springs secured to opposite walls of said lower section at points beneath said flange and bearing against said flange to retain them out of contact with corresponding walls of the second section, each of said
10 springs having two openings arranged one above the other adapted to have said studs

entered into either the upper or lower openings of said springs to retain the upper section in raised position or in telescoped position.

15

In testimony whereof I affix my signature in presence of two witnesses.

JAMES SHEWAN.
